UNITED STATES PATENT OFFICE.

EMERY J. DASHNER, OF BELMONT, AND CHARLES H. FLINT, OF NEWTON, MASSACHUSETTS.

PRESSURE-INDICATING DEVICE AND ALARM SIGNAL.

Application filed May 11, 1920. Serial No. 380,909.

To all whom it may concern:

Be it known that we, EMERY J. DASHNER and CHARLES H. FLINT, citizens of the United States of America, and residents of Belmont and Newton, in the county of Middlesex and State of Massachusetts, have invented certain new and useful Improvements in Pressure-Indicating Devices and Alarm Signals, of which the following is

10 a specification.

This invention relates to visible alarms for motor cars and particularly to alarms of this character adapted to be actuated by oil pressure to indicate the operation of the 15 oil circulating system, said alarm also being adapted to operate should the switch be left on when the car is not in use.

The invention has for its object the provision of a simple but effective device for 20 lighting a lamp when the pressure in the oil system is below a predetermined pressure, said device being placed in and out of commission by the same electric switch which completes the ignition circuit and 25 controls the operation of the engine.

The invention consists primarily in providing the oil circulating system with a closed compartment, having a diaphragm therein adapted to be moved by the oil in 30 said system when it reaches a predetermined pressure and break the circuit to the lamp thus extinguishing the light and indicating to the driver that a greater pressure of oil is required.

35 The invention further consists in controlling the operation of the lamp circuit by the same switch that controls the ignition circuit of the engine so that if the lamp remains lit when the car is not in use, a 40 warning will be given that the main switch has not been opened.

The invention further consists of certain novel features of construction and arrangement of parts which will be understood 45 readily by reference to the description of the drawings and to the claims to be hereinafter given.

For the purpose of illustrating the invention, one preferred form thereof is illustrated in the drawings, this form having been found to give satisfactory and reliable results although it is to be understood that the various instrumentalities of which the invention consists can be variously arranged 50 and organized and the invention is not

limited to the precise arrangement and organization of these instrumentalities as herein shown and described, except as required by the scope of the appended claims.

The drawing is a diagrammatical view, 60 partly in section, of an alarm system embodying the principles of the present invention.

In the drawings, 10 is a gasoline engine of any usual construction provided with a 65 cylinder 11, a piston 12, and a revoluble shaft 13.

The shaft 13 has secured thereto, a crank 14 connected to the piston 12 by the link 15. The shaft 13 has an oil chamber 16 70 therein, lubricating oil being admitted thereto through the radial passage 17. The shaft 13 revolves in bearings 18 from which extends a passage 19 between the flanges of the crank casing 20.

The outer end of the passage 19 communicates with a pipe 21, the opposite end of which communicates with an oil chamber 22 beneath the crank casing 20 and communicating therewith by a passage 23.

75 In the oil chamber 22 is a device 24 for forcing the oil through the pipe 21 and into the bearings of the shaft 13 and crank 14. This oil-forcing device or pump 24 may be of any well-known construction.

80 From the pipe 21 extends a branch pipe 25 on the opposite end of which is mounted the usual pressure gage 26.

85 At any convenient point on the car there is mounted a closed chambered casing 27 divided into two compartments by a diaphragm 28. The lower compartment 29 communicates by means of a pipe 30 with the branch pipe 25.

90 Superimposed upon the diaphragm 28 is an annular member 31 having at the upper end thereof a contact member or flange 32.

100 Adjustably mounted in the casing 27 is a stop member 33 which may be adjusted to limit the upward movement of the diaphragm 28, this member 33 being in axial alignment with the center of said diaphragm 28.

When adjusted, the member 33 is locked in position by means of the locking nut 34.

105 A spring 35 surrounds the stop member 33 and retains the contact member 31, 32 in position on the diaphragm 28.

110 In the casing 27 there is also mounted an insulating member 36 to which is threaded

a rod 37 having a contact member 38 on the lower end thereof.

This rod 37 may be adjusted endwise and locked in position by means of the 5 locking nut 39.

When there is no oil pressure within the circulating system 21, 25 and 30, the diaphragm is in the position indicated in the drawing with the movable contact member 10 32 in contact with the normally fixed contact member 38.

From the rod 37 extends a wire 40 to a lamp 41 which is connected by a wire 42 to a switch 43. The opposite end of this 15 switch 43 is connected by a wire 44 to a battery 45 and then by wire 46 to the ground 47.

The switch 43 is also connected by a wire 48 to a coil 49, the opposite end of which 20 is connected by a wire 50 to a distributor 51.

This distributor 51 is connected by a wire 52 to a spark plug 53 in the upper end of the cylinder 11.

When the engine is in operation, the 25 pump 24 will be actuated to force oil under pressure through the oil circulating system into the bearings on the various parts of the engine and also into the chamber 29 beneath the diaphragm 28.

30 When the oil pressure reaches a predetermined point, the diaphragm 28 will be moved upwardly and thereby cause the movable contact member 32 to be separated from the normally fixed contact member 38 and break the circuit.

This breaking of the circuit will extinguish the lamp 41 which is placed on the car where it is in view of the driver at all times. When the car is in use, if the lamp 40 41 is not lit the driver will know that there is a proper circulation of the lubricating oil but should the lamp at any time become lighted, he will at once be informed that the pressure in the oil circulating system 45 has reached a point below normal and that an additional amount of oil is required for the proper operation of the system.

By means of this circuit breaker, the lubricating system will be operative on all 50 grades over which the car is passing as the operation of the device does not depend upon the level of the oil either in the crank casing or in the external compartment connected thereto.

The ignition system 48, 49, 50, 51, 52 and 53 being also connected to the main switch 43, if the car should happen to be left with the switch on and the engine stalled, as 60 soon as the pump 24 fails to operate, the pressure in the oil circulating system will decrease to such an extent that the diaphragm 28 will return to its normal position and the members 32, 38 come into contact and complete the electric circuit there-

by causing the lamp 41 to be lighted to warn the driver that the switch is "on" and should be moved into "off" position.

In other words, the lamp 41 is a warning signal for the proper operation of the oil 70 circulating system while the car is in use and a warning as to the position of the main switch 43 when the car is not in use.

This is of considerable importance as it often happens that the engine becomes 75 stalled just at the time that the driver is prepared to leave the car for a long period and as the engine is not running he is liable to fail to open the switch and as a consequence of this failure, the battery is liable 80 to be used up and often over-heated to such an extent as to injure the parts on the car adjacent thereto.

It is believed that the operation and many advantages of the device will be fully 85 understood from the foregoing description.

Having thus described our invention, we claim—

1. In a device of the class described, an internal combustion engine; an oil circulating system for said engine; means driven by said engine for forcing oil under pressure through said system; an ignition circuit including an ignition switch for said engine; a signaling circuit controlled by 90 said ignition switch and including a signal; and means controlled by the pressure in said circulating system for maintaining said signal circuit open when the pressure in said circulating system exceeds a predetermined value but permitting it to close when the pressure falls below the predetermined value and the ignition circuit is closed.

2. In a device of the class described, an internal combustion engine; an oil circulating system; mechanical means driven by the engine for forcing oil under pressure through said system; an ignition circuit for said engine including a switch; a signaling circuit controlled by said switch and including a signal; and a circuit breaker in 105 said signaling circuit and controlled by the pressure in said oil circulating system whereby the signaling circuit will be maintained open when the pressure exceeds a predetermined value but will be permitted to close when the pressure falls below the predetermined value and the ignition circuit is closed.

3. In a device of the class described, an internal combustion engine; an oil circulating system for said engine; mechanical means driven by the engine for forcing oil under pressure through said system; an ignition 115 circuit for said engine including an ignition switch; a signaling circuit controlled by said ignition switch and including a signal; and means in said circulating system adapted to maintain the signaling circuit open when the 120 130

pressure in said circulating system exceeds a predetermined value but permits it to close when the pressure falls below the predetermined value and the ignition circuit is closed.

- 5 4. In a device of the class described, an internal combustion engine; an oil circulating system for said engine; mechanical means driven by the engine for forcing oil 55 under pressure through said system; an ignition circuit for said engine including a switch; a signaling circuit controlled by said ignition switch and including a signal; and means controlled by the decreased pressure 60 10 in the oil circulating system for actuating the signal until the ignition circuit is broken.
- 5 5. In a device of the class described, an internal combustion engine provided with a compartment containing oil and having a discharge pipe extending therefrom; a pump driven by the engine for forcing oil under pressure from said compartment into 65 said pipe; an oil circulating system with 20 which said pipe communicates; an ignition circuit for said engine including an ignition switch; a signaling circuit controlled by said ignition switch and including a signal; and means controlled by the pressure in said 70 25 oil circulating system for maintaining said signal circuit open when said pressure exceeds a predetermined value but permitting it to close when the pressure falls below the predetermined value and the ignition circuit 75 30 is closed.
- 5 6. In a device of the class described, an internal combustion engine provided with a compartment containing oil and having a discharge pipe extending therefrom; a pump driven by said engine for forcing oil under pressure from said compartment into 80 said pipe; an oil circulating system with 40 which said pipe communicates; an ignition circuit for said engine including an ignition switch; a signaling circuit controlled by said 85 45 ignition switch and including a signal; and means controlled by the pressure in said oil circulating system for maintaining said signal circuit open when said pressure exceeds a predetermined value but permitting it to 90 50 close when the pressure falls below the predetermined value and the ignition circuit is closed.

close when the pressure falls below the predetermined value and the ignition circuit is closed.

7. In a device of the class described, an oil circulating system; means driven by the engine for forcing oil under pressure through said system; an electric circuit including a switch; a signaling circuit controlled by the pressure in said oil circulating system for maintaining said signal circuit 60 open when the pressure in said device exceeds a predetermined value but permitting it to close when the pressure falls below the predetermined value and the switch in said electric circuit is closed. 65

8. In a device of the class described, an oil circulating system; mechanical means driven by the engine for forcing oil under pressure through said system; an electric circuit including a switch; a signaling circuit controlled by said switch and including a signal; and means controlled by the pressure in said circulating system for maintaining said signal circuit open when the pressure in said circulating system exceeds a 70 75 predetermined value but permitting it to close when the pressure falls below the predetermined value and the switch in said electric circuit is closed.

9. In a device of the class described, an oil circulating system; mechanical means driven by the engine for forcing oil under pressure through said system; an electric circuit including a switch; a signaling circuit controlled by said switch and including 80 a lamp; and means controlled by the pressure in said circulating system for maintaining said signal circuit open when the pressure in said circulating system exceeds a 85 predetermined value but permitting it to 90 close when the pressure falls below the predetermined value and the switch in said electric circuit is closed.
